Inventor.

Joseph W. Fiske

United States Patent Office.

JOSEPH W. FISKE, OF NEW YORK, N. Y.

Design No. 5,025, dated June 20, 1871.

DESIGN FOR FOUNTAINS.

The Schedule referred to in these Letters Patent and making part of the same.

To all whom it may concern:

Be it known that I, JOSEPH W. FISKE, of New York, in the county and State of New York, have invented and produced a new and original Design for Drinking-Fountains, of which the following is a specification.

There are four basins around the column, namely, a small basin on the upper part for passers-by; one large basin in the middle for large quadrupeds; and on the lower part of the column there are two basins for small quadrupeds—one on each side. Besides, there is a figure on the top of the column.

The nature of my design is otherwise fully represented in the accompanying drawing, to which reference is made.

Claim.

I claim as my invention—
The design for a drinking-fountain, as shown.

JOSEPH W. FISKE.
